Inventor.
Henry G. Saal

By G. A. Gray, C. I. O.

UNITED STATES PATENT OFFICE.

HENRY G. SAAL, OF CHICAGO, ILLINOIS.

RADIANT-ENERGY RECEIVER.

Application filed May 11, 1922. Serial No. 559,990.

To all whom it may concern:

Be it known that I, HENRY G. SAAL, citizen of the United States, residing at Chicago, in the county of Cook and State of Illinois, have invented a certain new and useful Improvement in Radiant-Energy Receivers, of which the following is a full, clear, concise, and exact description.

My invention relates to receivers for radiant electric energy of the type known as crystal detectors which employ a crystal body and energy conducting wire at one face of such body.

The invention has for its object the provision of an improved mounting for the wire whereby it may be adjusted into effective relation with the crystal body. In carrying out the invention I employ a rod that carries the wire, a block supporting said rod, a support formed with a seat that receives said block that is capable of adjustment on said support, and a spring which presses the block upon the support to hold it in its various adjustments.

In the preferred embodiment of the invention the support for the block is in the form of a hollow post which has a spherically curved seat at its upper end that receives the block which is also spherically curved where it engages the post to be capable of adjustment in all directions upon the seat. The spring that presses the block upon its support is preferably a coiled spring within the hollow of the post and which serves to connect the block and post whereby the block and post are maintained in assembly while permitting the wide range of adjustment for the block without the necessity of manipulating any device for maintaining the adjustment, the spring also performing this latter function. The rod is in sliding relation to the block that carries it so that the wire may be adjusted with respect to the crystal body not only by adjustment of the block which carries the wire supporting rod but also by adjustment of this rod.

I will explain my invention more fully by reference to the accompanying drawing in which Fig. 1 shows the preferred embodiment of the invention with some of the parts shown in sectional elevation and some in full elevation; and Fig. 2 is a plan view with the block that carries the rod shown in section.

Like parts are indicated by similar characters of reference in both figures.

Any suitable form of mounting, such as the plate 1 of insulation, may be employed for the parts that comprise the invention. The crystal body 2, such as galena, is provided upon the crystal mounting 3 which is formed with a threaded stem 4. The plate 1 is clamped between the base of the mounting 3 and the nut 5 that is screwed upon the threaded stem 4. A hollow post 6 is similarly formed with a threaded extension 7, the plate 1 being clamped between the base of the post 6 and the nut 8 which is screwed upon the post extension 7. The post is hollow from end to end and is formed with a spherically curved seat at its upper end to receive a block 9 which is preferably in the form of a ball, the lower side of the block, at least, being of spherical curvature.

The block is capable of adjustment in universal directions upon the post and is maintained in assembly with the post in each of its adjustments by means of a coiled spring 10 which is connected at one end with the stem 11 provided upon the element 9 and at its other end with a stirrup 12. The spring is under sufficient tension to hold the block 9 upon the upper end of the post 6 and the stirrup 12 against the bottom end of the post. The element 9 is formed with a diametrical bore in which the rod 13 has snug sliding engagement with the element 9. A flexible wire 14 is assembled with the rod 13 in any suitable way and terminates at the crystal block 2 as is understood. Circuit wires 15 and 16 are respectively assembled with the nuts 8 and 5. The wires 14 and 15 are electrically connected through the metallic elements 8, 6, 9 and 12.

While I have herein shown and particularly described the preferred embodiment of my invention, I do not wish to be limited to the precise details of construction shown as changes may readily be made without departing from the spirit of my invention, but having thus described my invention I claim as new and desire to secure by Letters Patent the following:

1. In a crystal detector, the combination with a crystal body; of a wire ending at one face of the crystal body; a rod carrying said wire; a block supporting said rod that

- is in sliding relation to the block; a hollow post formed with a spherically curved seat at its upper end that receives said block that is also spherically curved where it engages the post to be capable of adjustment; and a coiled spring connecting the block and post and within the hollow of the latter and serving to press the block upon the post and hold it in its various adjustments. 35
5. In a crystal detector, the combination with a crystal body; of a wire ending at one face of the crystal body; a rod carrying said wire; a block supporting said rod; a hollow post formed with a curved seat at its upper end that receives said block that is also curved where it engages the post to be capable of adjustment; and a coiled spring connecting the block and post and within the hollow of the latter and serving to press the block upon the post and hold it in its various adjustments. 40
10. 2. In a crystal detector, the combination with a crystal body; of a wire ending at one face of the crystal body; a rod carrying said wire; a block supporting said rod; a hollow post formed with a spherically curved seat at its upper end that receives said block that is also spherically curved where it engages the post to be capable of adjustment; and a coiled spring connecting the block and post and within the hollow of the latter and serving to press the block upon the post and hold it in its various adjustments. 45
15. 3. In a crystal detector, the combination with a crystal body; of a wire ending at one face of the crystal body; a rod carrying said wire; a block supporting said rod that is in sliding relation to the block; a hollow post formed with a seat at its upper end that receives said block that is capable of adjustment on said post; and a coiled spring connecting the block and post and within the hollow of the latter and serving to press the block upon the post and hold it in its various adjustments. 50
20. 4. In a crystal detector, the combination with a crystal body; of a wire ending at one face of the crystal body; a rod carrying said wire; a block supporting said rod that is in sliding relation to the block; a hollow post formed with a seat at its upper end that receives said block that is capable of adjustment on said post; and a coiled spring connecting the block and post and within the hollow of the latter and serving to press the block upon the post and hold it in its various adjustments. 55
25. 5. In a crystal detector, the combination with a crystal body; of a wire ending at one face of the crystal body; a rod carrying said wire; a block supporting said rod that is in sliding relation to the block; a hollow post formed with a seat at its upper end that receives said block that is capable of adjustment on said post; and a coiled spring connecting the block and post and within the hollow of the latter and serving to press the block upon the post and hold it in its various adjustments. 60

In witness whereof, I hereunto subscribe my name this 6th day of May A. D., 1922.

HENRY G. SAAL.
